UNITED STATES PATENT OFFICE.

ARMAND HERSON, OF MEUDON, FRANCE, ASSIGNOR TO OVIDE AUGER, OF VILLE LA SALLE, QUEBEC, CANADA.

WALKING CHAIR FOR CHILDREN.

Application filed December 30, 1921. Serial No. 525,850.

To all whom it may concern:

Be it known that I, ARMAND HERSON, a citizen of France, residing at Meudon, Seine and Oise, in France, Europe, have invented certain new and useful Improvements in Walking Chairs for Children; and I hereby declare that the following is a true, clear, and exact description of the same.

The present invention relates to an improved walking chair for children, which will be hereinafter fully described and is illustrated in the accompanying drawing.

In the drawing:—

Figure 1 is a side elevation of the invention in combination with a collapsible table.

Figure 2 is a bottom view of the table and chair folded.

Like numerals of reference indicate corresponding parts in each figure.

Referring to the drawing, 1 is a square block, on each side of which is pivotally secured a standard or leg 2, and 3 are rods having hooks 4 at one end and adapted to engage eyelets 5 to rigidly secure said standards together.

On said square block 1 is pivotally connected a turn table 6, and 7 is a member or arm preferably pivotally secured at its inner end at 8 to the table by means of the thumb screw 9, so that it may be moved alternatively from an inoperative position in which it is disposed entirely within the confines of the table, to an operative position in which its outer portion projects outwardly beyond the table, and vice versa. The said member 7 is provided with a hole 9^a, and 10 is a seat secured below said hole 9^a by means of inverted U-shaped member 11. At the outer or free end of said member 7 is pivotally secured the extensible post 12, and 13 is a roller on the lower end of said post; the post being movable between a vertical position in which its roller engages the floor, and one in which it is folded or collapsed against or close to the under side of the table.

In the operation of the invention, a child is placed in said hole 9^a, seated astride on the seat 10. His legs will naturally rest on the floor and by moving them he will revolve the turn table 6 and will in turn revolve therewith.

As illustrated in Figure 2 of the drawings, the invention can readily be folded 55 to take very little space when not in use.

What I claim as my invention is:—

1. A baby walker, comprising a stationary support; a turntable rotatably mounted on the top thereof; an arm pivoted at its inner end to the under side of the turntable for movement alternatively into a position in which it projects outwardly beyond the table at its outer end, or into one in which it is disposed against the said underside of the table and wholly within the confines thereof, and adapted to be releasably secured in either position, the projecting portion of said arm having an opening for the insertion of a baby therethrough; and a supporting seat for the baby to sit on suspended from said arm and disposed directly below said opening.

2. A baby walker, comprising a turntable; a support therefor; an arm pivotally connected at its inner end to the turntable for movement into and out of a position in which it projects outwardly beyond the table at its outer end, and adapted to be releasably secured in such position; a supporting seat for the baby to sit on carried by the outer portion of said arm; and a post for bracing the pivoted arm pivotally connected to the outer end of said arm for movement into and out of vertical, floor-engaging position.

3. A collapsible baby walker, comprising a turntable; a block whereon said table is rotatably mounted; a plurality of supporting legs pivotally connected at their upper ends to said block for movement alternatively into floor-engaging position or into collapsed position against the under side of the table; detachable brace connections between the several legs; an arm pivotally connected at its inner end to the table for movement alternatively into a position in which it projects outwardly beyond the table at its outer end or into one in which it is disposed entirely within the confines of the table, and adapted to be releasably secured in either position; and a supporting seat carried by the projecting outer portion of said arm.

4. A collapsible baby walker, comprising a turntable; a block whereon said table is rotatably mounted; a plurality of supporting legs pivotally connected at their upper ends to said block for movement alternatively into floor-engaging position or into collapsed position against the under side of

the table; detachable brace connections between the several legs; an arm pivotally connected at its inner end to the table for movement alternatively into a position in which 5 it projects outwardly beyond the table at its outer end or into one in which it is disposed entirely within the confines of the table, said arm adapted to be releasably secured in either position and having an opening formed adjacent its outer end for the 10 insertion of a baby therethrough; a sup-

porting seat for the baby carried by said arm and disposed directly below said opening; and a post pivoted to the outer end of said arm for movement alternatively into 15 floor-engaging position or into collapsed position against the under side of the table.

Signed at Meudon (Seine & Oise) France.
ARMAND HERSON.
